J. Trabucco
ATTORNEY.

UNITED STATES PATENT OFFICE

ANTON T. WEHNER, OF SAN FRANCISCO, CALIFORNIA

PERMANENT-HAIR-WAVING APPARATUS

Application filed January 27, 1930. Serial No. 423,758.

This invention relates to improvements in apparatus for use in the art of permanent hair waving.

An object of my invention is to provide an improved permanent hair waving apparatus embodying novel means for maintaining a heating element in operating position adjacent the hair to be treated.

Another object of my invention is to provide improved apparatus for use in hair waving having novel means embodied therein for protecting a person's head from heated water, moisture or steam resulting from a hair waving or treating operation.

A further object of my invention is to provide improved apparatus for use in permanent hair waving, embodying novel means for applying heat to strands of hair to be treated.

A still further object of my invention is to provide novel and improved apparatus for use in permanent hair waving, embodying compact means for confining the vapors resulting from a hair waving process to a definite area surrounding the hair being treated.

Other objects more or less apparent will present themselves or will be specifically pointed out in the description to follow.

In the accompanying drawings:

Figure 1 is a vertical sectional view of my improved permanent hair waving apparatus, showing the same in operative position with a strand of hair therein, a part of the apparatus being shown in perspective;

Figure 2 is a perspective view of a heating element constituting a part of my invention;

Figure 3 is a perspective view of an enclosing clamping member constituting a part of my invention; and

Figure 4 is a perspective view of a protecting shield constituting a part of my invention.

Referring to the drawings the numerals 1 and 2 represent clamping blocks suitably attached together as by a hinge, the said blocks each carrying a rubber pad 3 on its inner face between which a strand of hair may be firmly held. The person's hair to be treated for the purpose of producing permanent waves

therein, is ordinarily clamped or otherwise suitably fastened to a spool 4 and thereafter firmly wound into a roll thereon. After the strand of hair has been properly wound about the spool, a semicylindrical shaped shield 5, constructed from aluminum or other suitable material, is positioned beneath the roll of hair with a part thereof positioned directly over the opening between the two blocks 2 and 3. The shield 5 is intended primarily to prevent moisture, steam or water resulting from the treatment of the hair, from passing between the blocks and injuring the person's scalp. The water or moisture which forms while the hair is being heated drops onto the shield 5, rather than onto the blocks and is thereby prevented from dropping onto the person's scalp.

In order to prevent the vapors resulting from a permanent waving process from escaping, a covering 6 of flannel or other suitable material is placed around a part of the roll of hair and over a part of the shield 5. Over the flannel covering 6 is ordinarily placed in the order given, a strip of paper 7 and a strip of metal gauze 8, the same being used to insure the confinement of the vapors to the area within the roll of hair. Detachably mounted over the roll comprising the hair, shield, covering and strips, is a clamping member 9 formed with semi-cylindrical sides which extend outwardly and inwardly at their top edges to form a semi-cylindrical shaped socket 10 within which an elongated heating element 11 is adapted to fit. The lower edges of the clamping member 9 extend inwardly toward each other and are adapted to press the covering 6 as well as the strips 7 and 8 against the roll of hair and the shield 5, thereby preventing the displacement of the various parts of the apparatus after they have once been placed in operating positions. The curved sides of the clamping member 9 do not meet at their top edges, thereby permitting the heating element 11 to contact with the strip 8 of metal gauze.

The heating element 11 is formed in the usual manner with a casing having a plurality of windings of fine wire therein, the said wires being suitably connected to the termi-

nals of an electric light plug for insertion into a socket.

Quantities of heat from the heating element 11 being confined to the space located inside the clamping member 9, and its semi-cylindrical socket 10, pass around and through the strips and covering, thereafter entering the roll of hair which is to be treated for producing permanent waves therein.

10 The shield 5 as well as the clamping member 9 may each be stamped from a single piece of material and thereafter formed into the particular shapes shown.

15 It is obvious to those skilled in the art that my improved permanent hair waving apparatus may be constructed in other forms equally as efficient as the one shown and described so for this and other apparent reasons I desire my invention included broadly within the 20 spirit of the appended claims.

Having described my invention what I claim is:

1. Permanent hair waving apparatus comprising a pair of clamping blocks between which a strand of hair is held, a spool about which the strand of hair is wound, a curved shield located above the blocks and beneath the spool, a clamping member having sides adapted to fit over the hair rolled on the spool, 25 a hollow socket formed integrally with the clamping member, and a heating element detachably mounted in the socket.

2. In permanent hair waving apparatus, a pair of clamping blocks between which a strand of hair is held, a spool about which the hair is wound, a clamping member extending around the spool, a hollow socket formed on the clamping member, and a heating element detachably mounted in the socket.

3. In permanent hair waving apparatus, a semi-cylindrical shaped clamping member adapted to extend partly around a roll of hair, a semi-cylindrical shaped socket formed integrally with the clamping member, the 40 said socket being closed at its top side and adapted to contain a heating element.

4. In permanent hair waving apparatus, a plurality of hair clamping members, the inner faces of which are positioned adjacent 45 each other when the members are in a clamped position, a spool located above the clamping members and a shield removably positioned over the top edges of the inner faces of the clamping members and between the 55 spool and the clamping members.

In testimony whereof I have affixed my signature.

ANTON T. WEHNER.
